UNITED STATES PATENT OFFICE.

JOHN G. POPE, OF BLOOMINGTON, ILLINOIS.

DRILL-PRESS ATTACHMENT.

SPECIFICATION forming part of Letters Patent No. 234,687, dated November 23, 1880.

Application filed April 23, 1880. (Model.)

To all whom it may concern:

Be it known that I, JOHN G. POPE, of the city of Bloomington, county of McLean, and State of Illinois, have invented a new and useful Improvement in Drill-Press Attachments for Cutting Flue-Sheets and other Purposes, of which the following is a full, clear, and exact description, reference being had to the accompanying drawings, in which—

10 Figure 1 is a plan view of an attachment embodying my invention. Fig. 2 is a cross-section taken on the line $x x$, Fig. 1. Fig. 3 is a cross-section taken on the line $y y$, Fig. 1. Fig. 4 is an end elevation of the cutter-head, and Fig. 5 is a cross-section of the same.

The object of my invention is to provide a simple and effective attachment to a drill-press, whereby the holes in a flue-sheet for the insertion of the flues may be easily and rapidly cut.

20 My invention consists in a metallic sleeve provided at one end with an enlarged socket, which couples over the cross-piece of a drill-press and is fastened thereto by set-screws, and having at the other end an outer flange, through which passes a short rod having rigidly attached at its outer end a pawl and at its inner end a handle for raising the pawl, the flange also being provided with a spring for holding the pawl in place. Within the 25 flanged end of the sleeve is inserted a spindle, which, at its inner end, fits within the drill-press socket, through which motion is communicated to it, while the sleeve remains stationary. Upon the outer end of the spindle is keyed a cutter-head provided with slots, in which cutters are inserted. The spindle is also provided with a novel feeding device, all of which will be hereinafter more fully explained, and pointed out definitely in the claims.

30 In the drawings, A represents a metallic sleeve, provided at one end with an enlarged socket, a , which slips over the cross-piece of a drill-press, to which it is fastened by set-screws a' . The sleeve A is provided at the 35 other end with an exterior flange, a^2 , through a hole in which passes the short rod a^3 , having rigidly attached at its outer end the pawl a^4 , and at its inner end, after passing through the short standard or support a^5 , having rigidly 40 attached the handle a^6 . The standard or sup-

port a^5 is rigidly attached to the sleeve A. On the rod a^3 , between the flange a^2 and the standard a^5 , there is also rigidly attached the cam or lever a^7 , and firmly attached at one end to the inner side of the flange is the curved spring a^8 , the outer end of which rests upon the cam or lever a^7 , and consequently presses it and the outer pawl down until it is raised up by the handle. Through the flanged end of the sleeve A passes the spindle B, the inner end of which fits within the drill-press socket, and is fastened thereto, in the usual manner, through an aperture, a^9 , in the sleeve A. On the outer portion of the spindle B there is keyed the steel flange C, with a slight depression, c , upon one portion of its edge, for a purpose hereinafter described. Upon the face of the flange adjacent to the sleeve is a curved plate, c' , with its outer edge corresponding to the edge of the flange C, and provided with a slot, c^2 , through which pass short set-screws c^3 , which fasten it to the flange C, and by their adjustment permit the plate c' to extend over more or less of the depression c in the flange C.

45 On the outer end of the spindle B there is keyed a cutter-head, D, provided with slots d , for holding the cutters d' , which are adjusted and fastened in the cutter-head by set-screws d^2 . The cutters d' are each provided with a cutting-edge in the usual form. The cutter-head is provided with a feather, d^3 , which fits within a keyway in the spindle, and is also provided on its inner side with a boss, d^4 , in which there is a groove, d^5 .

50 The spindle B is provided, for a suitable distance beyond the flange C, with a left-hand screw-thread, b , upon which there is screwed the nut E. This nut is provided on its end adjacent to the flange C with a flange, e , which is a trifle smaller in diameter than the flange C, and teeth are cut around its edge so as to give it the form of a ratchet-wheel. The other end of the nut is recessed so as to pass over the boss d^4 , and set-screws e' pass through the nut 55 and engage in the groove d^5 , so as to turn freely therein and permit the nut to work independently. A hand-wheel, F, is fastened rigidly to the nut E by a set-screw, by which means the nut can be turned home after it has 60

been fed out, as hereinafter explained. The outer end of the spindle B is preferably formed into a center punch point.

The operation of my device is as follows: 5 After the several parts have been adjusted in place, as hereinbefore described, the flue-sheet in which it is desired to cut holes is placed immediately under the cutter-head D, and motion is communicated to the spindle B, while 10 the sleeve A remains stationary. With each revolution of the spindle B the pawl a^4 , when it comes to the depression e in the flange C, drops within it, owing to the tension of the spring a^6 , and consequently engages in the 15 teeth upon the edge of the flange e of the nut E. As the spindle continues to revolve, the nut is held stationary by the pawl a^4 , and therefore the spindle turns in the nut, which feeds the cutter-head along the spindle till the 20 continued revolution of the spindle carries the depression e along beyond the pawl a^4 , which is consequently raised out of contact with the teeth upon the edge of the flange e until the 25 depression is again reached upon another revolution, when the same process is repeated, the spindle being turned in the nut and the cutter-head fed down a slight distance at each revolution. This distance is determined by the adjustment of the plate c' , so as to have a 30 longer or shorter depression, e , in the flange C.

When, by the advance of the cutter-head, a

hole is bored through the flue-sheet, the motion is stopped, and by raising the handle a^6 the pawl a^4 is removed from contact, and by turning the hand-wheel in the proper direction 35 35 the nut is brought back to the place of beginning, when the process is repeated as before.

By the use of the above-described attachment holes of the required size may be cut in 40 flue-sheets very rapidly, and with a great saving of time and labor over the methods heretofore employed for that purpose. It is also applicable to drills and other uses.

Having thus described my invention, what I 45 claim as new, and desire to secure by Letters Patent, is—

1. The combination of the sleeve A, provided with flange a^2 , the pawl a^4 , and the spindle B, having a flange, C, provided with the 50 curved plate c' , with the flanged nut E and the cutter-head D, substantially as and for the purpose set forth.

2. The combination of the sleeve A, provided with flange a^2 and pawl a^4 , and the spindle B, provided with a flange, C, the flanged 55 nut E, and the cutter-head D, substantially as and for the purpose described.

JOHN G. POPE.
